UNITED STATES PATENT OFFICE.

CHARLES H. HOWE, OF LEOMINSTER, MASSACHUSETTS.

DESIGN FOR A HAIR ORNAMENT.

SPECIFICATION forming part of Design No. 36,628, dated November 17, 1903.

Application filed June 11, 1903. Serial No. 161,117. Term of patent 7 years.

To all whom it may concern:

Be it known that I, CHARLES H. HOWE, a citizen of the United States, residing at Leominster, in the county of Worcester and State of Massachusetts, have invented a new, original, and ornamental Design for a Hair Ornament, of which the following is a specification, reference being had to the accompanying drawings, in which—

Having illustrated my design, what I claim as new, and desire to secure by Letters Patent, is—

The ornamental design for a hair ornament as herein illustrated.

CHARLES H. HOWE.
